CLAIM

We claim the ornamental design for an appliance door handle, as shown and described.

DESCRIPTION

FIG. 1 is a front, right perspective view of an appliance door handle showing our new design in environmental use mounted on an oven door;

FIG. 2 is a top, front perspective view of the appliance door handle of FIG. 1;

FIG. 3 is a bottom, back perspective view of the appliance door handle of FIG. 1;

FIG. 4 is a top view of the appliance door handle of FIG. 1; FIG. 5 is a bottom view of the appliance door handle of FIG. 1;

FIG. 6 is a front view of the appliance door handle of FIG. 1;

FIG. 7 is a back view of the appliance door handle of FIG. 1;

FIG. 8 is a left side view of the appliance door handle of FIG. 1; and,

FIG. 9 is a right side view of the appliance door handle of FIG. 1.

The broken lines in FIG. 1 are included for the purpose of illustrating portions of the environment in which the appliance door handle is used and form no part of the appliance door handle design as claimed in FIG. 1.
